UNITED STATES PATENT OFFICE.

GEORG KIRKEGAARD, OF NEW YORK, N. Y., ASSIGNOR TO IMPERIAL STOPPER COMPANY,
A CORPORATION OF MAINE.

BOTTLE-CAPPING MACHINE.

No. 926,425.

Specification of Letters Patent.

Patented June 29, 1909.

Application filed October 1, 1908. Serial No. 455,774.

To all whom it may concern:

Be it known that I, GEORG KIRKEGAARD, a citizen of the United States, residing at the city of New York, in the borough of Brooklyn 5 and State of New York, have invented certain new and useful Improvements in Bottle-Capping Machines, of which the following is a full, clear, and exact description.

My invention relates to bottle capping machines of the type having a cap applying head adapted to be depressed upon a bottle, the latter being supported by a table which resists the downward thrust of the cap applying operation. A certain predetermined resistance to pressure must be provided in all cases, but the varying heights of different bottles due to imperfect manufacture or otherwise should be compensated for, so that tall bottles will not be crushed and broken, 20 while the shorter bottles will be certain to receive adequate pressure.

One of the objects of the present invention is to provide a form of table which shall afford an adequate resistance against depression, so that the cap will be properly applied, but which automatically yields or compensates its position to bottles of differing sizes.

A further object of the invention is to provide a magnetic system for securing the force of reaction in the table and which furnishes a resistance free from the effects of inertia, so as to present a force of definite magnitude regardless of the suddenness of impulse of the 35 cap applying head, and regardless of any varying dimensions in the bottle.

A third object of the present invention is to provide a system of electrical contacts in conjunction with the electro magnet, to cause the latter to present a substantially uniform resistance against depression of the table regardless of the position to which the table is moved, depending on the height of the bottle.

With these and other objects in view, the invention consists of the features of construction and combination as hereinafter set forth and claimed.

In the drawings: Figure 1 is a side elevation, partly in section, showing a cap applying machine embodying the principles of my invention. Fig. 2 is a diagrammatic view showing a slightly modified form of the invention.

1 designates the cap applying head, which 55 is guided and controlled by mechanism (not shown) to have a vertical movement through a predetermined range.

2 designates a table on which the bottle to be capped is received and which is depressible with a predetermined force of resistance of reaction so as to compensate for the varying sizes of the bottles and also slight inequalities in the caps.

In practice, the depression of the cap applying head is made greater than is necessary for any ordinary bottle, in order to insure that an adequate depression is afforded for the smallest sizes. Under these circumstances the table 2 always yields more or less 70 in every capping operation, and it should yield without increasing its resistance against depression, even for the largest and tallest bottles.

The table 2 is made with a depending circumferential flange 3, which loosely surrounds and telescopes upon the tubular extremity 4 of the casing 5, forming part of the frame of the machine.

6 designates a magnet coil or solenoid contained within the casing 5, and adapted to attract upward an iron core 7 vertically movable therein. The core 7 is connected with the table 2 by a stem 8, made of brass or non-magnetic material, and a spring 9 is provided 85 within the tube 4 and surrounding the stem 8 to maintain the table normally elevated to its upper limit of movement. This limit of movement of the table may be fixed by any suitable stop, such as a collar 10 surrounding 90 and fixed to the core 7 so as to abut against the lower side of the electro magnet coil.

11 denotes a spring plate or brush fixed to the core 7, and adapted to engage a plurality of contacts 12 mounted in a vertical series 95 on an insulated block 13. The block 13 may be supported in any suitable way from the casing 5, conveniently in the wall of a cup shaped chamber 14 directly beneath the electro magnet, and adapted to receive the core 7 100 in its downward movement.

The electrical circuits of the solenoid are made from any suitable current source 16 by connections established through the contacts 12 and the brush 11. The magnet 6 is sectionally wound, the different sections being, however, serially connected together, and forming in effect one continuous winding

with tapped off leads or connections 17, 17' and 17''. The current source 16 is connected to the other end of the magnet winding by wire 18 at one terminal, and has its other terminal joined to the brush 11 by the wire 19.

The use in operation is as follows: The machine being started in operation, the cap applying head 1 normally reciprocates vertically through a fixed range of movement. 16 Bottles 20 are placed on the table 2 in the path of the cap applying head, which descends and applies the cap in a manner forming no part of the present invention. Any suitable mat 21, of rubber or similar substance, is interposed between the bottle and the table 2, so as to compensate for any minor irregularities in the bottom surface of the bottle.

In the normal condition of the apparatus, 20 the circuit of the magnet 6 is not completed, owing to the fact that brush 11 is not depressed into engagement with any of the contacts 12. The device, therefore, does not waste current when not in use. As soon, 25 however, as the bottle has been partly depressed by the engagement of the cap applying head, the brush 11 engages the initial contact of the series 12 and completes the circuit through the entire magnet winding. 30 The upward attraction of the magnet on its core 7, caused by this energization can be made a force of any predetermined value exactly according to the needs of the cap applying operation. The value of this force is 35 substantially independent of any slight variation in the depression of the core due to bottles of slightly varying heights. In the case of a depression of more than a certain amount, however, an excessive force might 40 be presented, and the series of contacts 12 and the sectional windings of the magnet are provided to prevent this. When the depression of the table 2, due to a particularly long bottle, exceeds a certain amount, the 45 brush 11 will engage the second contact 12, by which the lower section of the magnet winding is cut out. The diminished magnetism acts more efficiently than before to attract the core upward, and the number of 50 turns in the magnet sections are so regulated that the resistance against depression of the core is substantially unchanged. In like manner, for extremely long bottles, the brush 11 engages the lowermost contact 12, 55 so that only the upper section of the electro magnet remains in circuit. By reasoning similar to that already considered, it will be seen that the resistance against depression of the core under these circumstances can 60 still be made unchanged. Any number of contacts may be provided extending to any required degrees of depression of the core 6, or the sectional windings of the magnet may be made so numerous and so individually 65 minute as to present substantially an un-

broken and perfectly uniform resistance against depression through the entire range of movement.

In the foregoing action the spring 9 has a negligible effect, being loosely spiraled and 70 comparatively light in its action. This spring is introduced only to lift the table 2 and the core 7 of the magnet against gravity, and is made of a strength and proportions designed to compensate for and counter-balance the weight of the parts mentioned 75 without having any other appreciable effect in the action.

In Fig. 2 I have illustrated a slightly modified construction by which a perfectly uniform resistance against depression of the table may be magnetically obtained. In this case the magnet winding is not sectional, but is connected in series with a resistance, the magnitude of which may be varied so as 80 to produce a diminished magnetization as the table descends, thereby compensating for the increased efficiency of the attractive force. The magnet, table and core are mounted and arranged substantially in the 85 same manner as in the preferred form of the invention, and are denominated by the same reference characters. In place of the brush 11, there is, however, provided a pivot connection 25 for an arm 26, fulcrumed at 27. 90 The connection of the pivot 25 with the core 7 may be made through any flexible link 28, so as to accommodate the angular movement of the pivot point. The lever 26 has a long metallic arm 26' moving over a resistance 100 element 29 of any suitable or desired material having a proper resistance coefficient. The metallic arm 26' is made one terminal of a circuit, including the winding 6 and the current source 16, the other terminal of the circuit being connected to the resistance element 29 at a point 30 closely adjacent to the position of initial engagement of the arm 26' therewith. The arm 26' is normally out of contact with the resistance element 29, as 105 shown in Fig. 2, but is moved so as to engage the same and permit a maximum current flow through the circuit when the table is very slightly depressed in the capping operation. As the table is still further depressed, 110 the arm 26' swings upward along the resistance element 29, cutting resistance into the circuit and diminishing the current flow to compensate for the increased efficiency of the magnetic attraction. The resistance element 29 may be of varying cross-section and empirically designed to give an absolutely 115 uniform reaction against depression of the table 2, regardless of the extent of such depression.

What I claim is:

1. In a bottle capping machine, a cap applying head, a table to support a bottle, and means for magnetically opposing the depression of the table.

2. In a bottle capping machine, a cap applying head, a table to support a bottle, means for magnetically resisting the depression of the table, and means acting thereon to maintain said resistance substantially uniform regardless of the extent of the depression.
3. In a bottle capping machine, a cap applying head, a table to support a bottle, a solenoid magnet, and means coöperating therewith to cause a magnetic resistance to the depression of the table.
4. In a bottle capping machine, a cap applying head, a table to support a bottle, a solenoid magnet, and means coöperating therewith to cause a substantially uniform magnetic resistance to the depression of the table.
5. In a bottle capping machine, a cap applying head, a table to support a bottle, a

sectionally wound magnet, and means co-operating with said magnet to cause a substantially uniform magnetic resistance to the depression of the table.

6. In a bottle capping machine, a cap applying head, a table to support a bottle, a sectionally wound solenoid, a core depressible in said solenoid and connected to said table, a plurality of contacts connected to the sections of said solenoid winding, and means moved by said core and engaging said contacts to cut out sections of said winding successively as the table is depressed.

In witness whereof, I subscribe my signature, in the presence of two witnesses.

GEORG KIRKEGAARD.
